ROBERT A. RUSSELL, OF RIDGEWOOD, NEW JERSEY.

RECEPTACLE CLOSURE.

Application filed June 21, 1924. Serial No. 721,471.

This invention relates to an improvement in receptacle closures and, more particularly, screw closures such as are used in connection with bottles, jars, and the like, containing foods, for example, catsup.

An object of the invention is to provide such a closure which has very effective means for preventing corrosion of its parts due to action engendered by the contents of 10 the receptacle, or due to other causes.

Another object consists in providing such a closure, the seams of which are rendered very tight to prevent leakage.

Another object consists in providing such 15 a closure which is made from sheet material that has previously been treated so as to cause the closure formed therefrom, without further treatment, to embody the above named features of advantage.

Another object consists in providing certain improvements in the form, construction and arrangement of the several parts whereby the above named and other objects 20 may be effectively attained.

A practical embodiment of the invention 25 is represented in the accompanying drawings, in which

Fig. 1 represents a detail side view, partly in section, showing the closure in sealing engagement upon the neck of a glass receptacle.

Fig. 2 represents a similar view showing the closure and receptacle after the element for holding the closure in sealing engagement has been stripped off.

Fig. 3 represents an enlarged detail section showing the seam uniting the top to the body of the closure, and adjacent parts.

Fig. 4 represents a detail plan view, partly broken away, of the sheet material from which the closure is made.

Fig. 5 represents a section taken in the plane of the line V—V of Fig. 4, looking in the direction of the arrows.

I have illustrated my invention as being applied to a closure which contains a threaded portion and also a tear-off strip or band at the lower edge thereof, which band is designed to be bent around a beading on the receptacle to seal the closure in position thereon. The tearing off of this band enables the unscrewing of the closure from the receptacle, and the former may be used as an ordinary screw closure thereafter until 55 the contents of the receptacle have been consumed.

The main body portion of the closure is denoted by 1. It is composed of sheet material and united in circular form by an interlocking seam 2. This body portion is 60 provided with suitable threads, in a well understood manner, for cooperation with the customary threads upon the receptacle 3; and the body portion may also have a knurling 4, as is usual, to assist in the manual operation of screwing it onto or unscrewing it from the receptacle.

The top of the closure is denoted by 5, and it may conveniently be united with the body portion 1 by an interlocking seam 70 marked 6, which operation may be performed by a die, as is well understood in the art.

It may be stated that the seams which unite the edges of the body portion and 75 which also join the top to the body portion are folded so as to cover and conceal the edges of the material.

The central portion of the top 5 is desirably depressed, as clearly shown in the 80 drawings, and the under side of the same is provided with a suitable sealing disc 7 which may conveniently be composed of cork composition, rubber compound, or other suitable yielding material. By forming the 85 top 5 with a depressed center, the screwing of the closure onto the receptacle tends to force the sealing disc not only against the outer edge of the neck of the receptacle, but also, to a slight extent, down within the 90 neck of the receptacle. This is a feature of advantage because it imparts a wedge-like action to the mutual engagement of the disc 7 with the receptacle 3, thereby affording a very tight seal; and also because it enables 95 the disc 7 to cover any tiny fissures which may exist in the neck of the receptacle just below its extreme outer edge, and thereby prevent leakage.

The lower part of the body portion 1 of 100 the receptacle includes a cylindrical depending strip or band 8, which is free of any screw thread. The parts are so proportioned that, when the closure is screwed firmly upon the receptacle, the band or strip 8 105 will be coincident with the usual beading 9 that is provided upon receptacles of this nature, immediately below the screw thread.

With the closure in this last named position, it is a simple matter for the band 8 to 110 be acted upon by seaming or spinning rollers, or gripping jaws, so as to crimp its

lower edge underneath the beading 9, as clearly shown in full lines in Fig. 1. It will be observed, at this juncture, that the lower edge of the band 8 is shown in its original cylindrical form in dotted lines in Fig. 1.

The act of thus spinning or bending the band or strip 8 around underneath the beading 9 sets up a firm locking engagement between the receptacle and the closure so as to hold the said parts in substantially hermetically sealed condition, thereby preventing the access of air to the contents of the receptacle, which is a matter of importance.

One end of the band 8 is developed in the form of a tongue 10 which overlaps to a considerable distance the remainder of the band. A scored or weakened line 11 is formed at the junction of the band 8 with the body portion 1 of the closure.

It is intended that the receptacle will be shipped and stored in sealed condition. When it is received by the consumer, it is only necessary for the latter to insert the thumb nail beneath the end of the tongue 10 and bend the same backwardly upon itself in order to obtain a firm grip thereupon. Continuation of this manual motion will tear the band 8 away from the body portion 1 at the scored or weakened line 11, thereby completely removing the band 8 both from the receptacle and from the closure. This operation at once breaks the locked sealing engagement, and the closure may be unscrewed to open the receptacle in the ordinary manner. The condition of the closure after the band or strip 8 has been removed is shown in Fig. 2, and it will be seen that there remains a complete slightly and satisfactory screw closure which may be used in the customary manner until the contents of the receptacle have been dissipated.

There is an important practical advantage in this closure arising from the fact that the element which provides for locking the closure in sealing condition is combined with a complete screw threaded closure, because the unsealing does not destroy the closure as a closure of general utility.

The sheet material from which the closure is made, and, of course, the closure made therefrom, constitute the basic features of my invention.

The material itself preferably consists of sheet metal, such as tin, which has been coated upon one or both sides with some anticorrosive substance, such as lacquer, printing colors, or the like. This sheet metal is represented by 12 (Fig. 5). To one side of the said sheet metal is secured, as by a suitable adhesive, a thin layer or sheet of fibrous material, such as oiled paper. This sheet is represented by 13.

As is well known, the tin is commonly

received in sheets of considerable size and it has been customary to lacquer it while in this form. I have found it practicable and desirable also to apply the fibrous sheet or layer 13 to the sheets of tin after the same have been lacquered and before they are cut up for the forming of the closures.

As oiled paper suitable for this purpose and an adhesive suitable for applying it to the sheet material, are both well known commercial articles, there is no need further to describe the character or composition of either.

By preference, the fibrous sheet 13 is applied to only one side of the sheet material 12 and, after these two parts have been caused firmly to adhere to each other, the composite sheet is cut up or blanked out and utilized for forming the closure in a well understood manner, care being taken to so dispose the material during the operations, that the fibrous sheet or layer 13 will be on the inside of the formed closure, as clearly shown in Figs. 1, 2 and 3.

This oiled paper, or the like, serves as a very efficient protective covering for the metal of which the closure is composed, so as to prevent the metal from corroding under the influence of acid or other agents contained in or engendered by the contents of the receptacle. It also prevents oxidation of the metal.

Heretofore, lacquering of the metal has commonly been relied upon for this purpose but, as any substantial friction upon or scraping of this lacquer will remove or partially remove it in spots, its protective action has not been entirely satisfactory. My coating or layer of oiled paper, or the like, adds so much protective value to the lacquer, that a closure free from any criticism in the respect just noted is practically assured. The great, if not vital, importance of having a closure for this class of receptacles, which is really proof against corrosion, is generally admitted by those familiar with this art, so that I regard the provision of this material for the manufacture of such closures, and closures manufactured therefrom, as very substantial advance steps.

This fibrous layer 13 not only serves to protect, as above described, but, owing to the fact that it is folded into the seams 2 and 6, it automatically acts as a packing for the said seams rendering them much tighter than they otherwise would be so as to prevent leakage of air or contents.

This fibrous layer also provides a certain yielding quality to the interior of the closure, thereby enabling it better to conform to any irregularities on the exterior of the receptacle.

While I have described and illustrated my invention in connection with a closure of a particular structure, I desire expressly

- state that the invention is not limited thereto, since I believe myself the first to construct a closure of sheet material provided with a fibrous layer adhering thereto.
- 5 It will be understood that various changes may be resorted to in the form, construction, composition and arrangement of the several parts without departing from the spirit and scope of my invention; and hence, I do not 10 intend to be limited to the details herein shown and described, except as they may be included in the claims.

What I claim is:

- 15 1. A receptacle closure composed of sheet metal having an anti-corrosion lamina of treated paper, or the like, adhering to a surface thereof, said closure including a folded seam and said lamina being folded into the seam and located on the inside of the closure.

2. A receptacle closure composed of sheet 20 metal having an anti-corrosion lamina and comprising, a body portion, said body portion being bent into cylindrical form and having the meeting edges thereof joined by a folded seam, and a top for closing the end 25 of said body portion, said top being joined to the body portion by a folded seam; said anti-corrosion lamina being composed of treated paper or the like firmly adherent to a surface of said sheet metal, located on the 30 inside of the closure and folded into the seams thereof, thereby protecting the metal and packing said seams to give them additional tightness.

In testimony, that I claim the foregoing 35 as my invention, I have signed my name this 19th day of June 1924.

ROBERT A. RUSSELL.
